UNITED STATES PATENT OFFICE.

FRED O. SPIES, OF ADAMS, NEW YORK.

CUTTER BOARD.

Application filed November 11, 1925. Serial No. 68,585.

This invention relates to a board designed primarily for use in connection with meat cutters and the like, one of the objects of the invention being to provide a simple and compact device of this character which is made up of a plurality of segments assembled to produce a smooth surface which will not splinter readily, efficient means being employed whereby the several segments can be held assembled, said means serving to anchor the segments together at their ends without presenting to the cutting element or elements any metal or other hard substance likely to dull the edge or edges of the cutting tool.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings, the preferred form of the invention has been shown.

In said drawings,

Figure 1 is a plan view of the device, a portion being broken away.

Figure 2 is a section on line 2—2 of Figure 1, the plug being shown in elevation.

Referring to the figures by characters of reference 1 designates a plurality of segmental blocks each of which is formed, in its outer edge, with a central groove 2 extending from one side edge to the other of the block so that, when the several blocks are assembled about a common center and in contact with each other, these grooves will register to form an annular groove. One of the blocks, which has been indicated at 3, is formed of two superposed sections resting flat upon each other and these sections have matching portions 4 cooperating to produce a portion of the circumferential groove heretofore referred to.

When all of the sections are assembled they fit tightly together and produce a circular board. The inner ends of the sections also define a circular opening 5 the wall of which is screw threaded so as to receive a screw threaded plug 6 of wood or other material corresponding with that of which the sections 1 are formed.

In assembling the parts of the board a

metal ring 7 is first provided, this ring having its ends welded together and the outer periphery of the ring being flat while the inner periphery thereof is rounded. In other words the material of which the ring is formed is substantially semi-circular in cross section as shown. The various segmental sections 1 are placed within the space surrounded by the ring and are positioned as close to the center of the ring as possible. They are then shifted outwardly radially until the grooves 2 therein receive the ring 7. By pressing these segments together a segmental space will be left between two of them, this space being just large enough to receive the split section 3. The members of this split section are placed in position above and below the ring and are glued together or otherwise fastened, thus completing the circular board. As a means for holding the segmental sections assembled with the ring so that they will not become jarred or out of place when the board is in use, the screw plug 6 is forced into the opening 5 so as to engage the threads upon all of the segmental sections of the board, thereby anchoring the inner ends of said sections to each other. The ends of the plug are dressed down so as to be flush with the corresponding faces of the board after which said board is ready for use.

It will be noted that there are no metal parts exposed where they are likely to injure the cutting tool employed in connection with the board. Furthermore by making the board out of segments the grain of the wood will be extended substantially in a circle about the center of the board and the segments are not likely to be chipped in use.

What is claimed is:

1. In a cutter board the combination with a ring, of segmental strips having registering grooves in their outer ends for the reception of the ring, a split segmental strip including superposed sections straddling the ring at the outer end and filling the space provided between two of the first named sections, and an anchoring plug inserted between the inner ends of the sections.

2. In a cutter board the combination with a ring, of one-piece segmental sections in the space surrounded by the ring and having grooves in their outer ends in which the ring is seated, said sections being in contact except between two of the sections, a segmental section comprising superposed por-

tions interposed between the spaced one-piece sections and cooperating to provide a groove for the reception of the ring, all of said sections cooperating to provide an unbroken surface extending around a central opening, and a plug fitted snugly within said opening for anchoring together the inner ends of all of the segmental sections.

3. In a cutter board the combination with
10 a ring, of one-piece segmental sections in
the space surrounded by the ring and having
grooves in their outer ends in which the ring
is seated, said sections being in contact except
between two of the sections, a segmental sec-
15 tion comprising superposed portions inter-
posed between the spaced one-piece sections

and cooperating to provide a groove for the reception of the ring, all of said sections cooperating to provide an unbroken surface extending around a central opening, and a 20 plug fitted snugly within said opening for anchoring together the inner ends of all of the segmental sections, said plug being screw threaded and there being threads upon the inner ends of the sections for engagement 25 with the plug, the ends of the plug being flush with corresponding faces of the sections.

In testimony that I claim the foregoing as my own, I have hereto affixed my signature.

FRED O. SPIES.
